(57) **CLAIM**

The ornamental design for a chimera shad glide bait, as shown and described.

DESCRIPTION

FIG. 1 is a top-front-left perspective view of a chimera shad glide bait showing my new design;

FIG. 2 is a bottom-front-right perspective view thereof;

FIG. 3 is a top-rear-left perspective view thereof;

FIG. 4 is a bottom-rear-right perspective view thereof;

FIG. 5 is an enlarged front elevational view thereof;

FIG. 6 is an enlarged rear elevational view thereof;

FIG. 7 is a top plan view thereof;

FIG. 8 is a bottom plan view thereof;

FIG. 9 is a right elevational view thereof;

FIG. 10 is a left elevational view thereof;

FIG. 11 is a cross-sectional view taken along line 11-11 in FIG. 5; and,

FIG. 12 is a cross-sectional perspective view taken along line 12-12 in FIG. 10.

The broken line showing a hinge mechanism in FIGS. 1-4 and 7-12, and the broken line showing internal bait components in FIG. 11 are included for the purpose of illustrating environmental structure and form no part of the claimed design.

1 Claim, 12 Drawing Sheets
